UNITED STATES PATENT OFFICE.

WILLIAM R. KINNEAR, OF COLUMBUS, OHIO.

METAL ROOFING.

SPECIFICATION forming part of Letters Patent No. 550,325, dated November 26, 1895.

Application filed March 18, 1895. Serial No. 542,198. (No model.)

To all whom it may concern:

Be it known that I, WILLIAM R. KINNEAR, a citizen of the United States, residing at Columbus, in the county of Franklin and State 5 of Ohio, have invented certain new and useful Improvements in Metal Roofing; and I do hereby declare the following to be a full, clear, and exact description of the invention, such as will enable others skilled in the art to 10 which it appertains to make and use the same.

My invention, relating more particularly to that class of metallic roofing which is made up of shingles previously stamped into proper form, has for its object to provide shingles 15 that shall be readily fitted together and securely locked without the use of nails or other extraneous fastenings, and at the same time may be easily and economically formed in dies or machinery. Incidental to these objects it is 20 also my aim to provide shingles which when united shall form a thoroughly waterproof and durable roof.

My invention is embodied in a shingle having on one edge a vertical flange or tongue 25 bearing projections or lugs, and on the opposite edge a folded part forming a groove, one of the walls of which bears lugs or projections, so that when a groove is placed on a tongue the lugs or projections of one part may 30 be forced under those on the other, and thus prevent the separation of the two shingles in a direction at right angles to the plane of the shingles.

In the accompanying drawings, illustrating 35 my invention, Figure 1 represents a perspective view of a piece of roofing made up of my shingles. Fig. 2 is a perspective view of a single shingle, one corner of the grooved edge of which is broken away to show the locking 40 lugs or projections. Fig. 3 shows an ornamental rib or molding that may be included in a roof made up of my shingles. Fig. 4 shows another way of applying the ornamental molding. Fig. 5 is still another way 45 of attaching the ornamental molding. Fig. 6 is an enlarged sectional view showing a cleat at the upper edge of the shingle.

Like characters of reference in the different figures designate corresponding parts.

50 1 designates the body of the shingle.

2 designates the vertically-standing flange or tongue on one edge and 3 the vertically-

standing groove or folded part at the opposite edge. Both the tongue and groove have formed therein, preferably by stamping, inclined lugs or projections 4, located at short intervals apart, so that when the grooved edge of one shingle is placed down on a tongue of another the projections or lugs 4 on the groove may, by a slight longitudinal movement of 60 the superposed shingle, be forced under the projections 4 of the tongue and the two shingles so locked from separation in a direction at right angles to the plane of the shingles. In constructing the roof, however, it will be 65 found desirable to put the shingles together so as to break joints—that is, the middle of the grooved edges of the shingles in one course will be placed over the points of connection of the shingles in the contiguous course. 70

To provide a water-shedding joint between the ends of the shingles in the same course I bend the upper part upwardly, forwardly, and then folded rearwardly, so as to form a groove 75 10, slightly elevated above the plane of the body of the shingle by the perpendicular part 5. The lower part of the shingle is folded under, so as to form a tongue 6, and the lower edge of the folded part is bent at an obtuse angle, as shown at 7, so that when the tongue 80 6 is inserted into the groove 10 the edge 7 shall project over the perpendicular part like the edge of a roof. By this construction water is shed from one shingle to another and leakage by capillary attraction avoided. 85

When it is desired to add an ornamental beading or molding to the roof, one of the courses of the two adjacent courses which are to receive the molding may have both its edges provided with tongues and lugs 4, and 90 the sections of molding or beading may have grooves formed by a double folding of the edge of the molding or beading, as shown in Fig. 3. In this form the locking lugs or projections 4 on the tongues may be stamped 95 outward—that is, on those sides of the tongues in adjacent courses of shingles that face each other.

In Fig. 4 I have shown a way to avoid forming a groove in the edges of the molding. In 100 this form the locking projections are stamped so as to project inward, and those on the tongues project from the inner side of the tongue. When the molding is thus con-

structed, the elasticity of the molding will suffice to hold the molding in place, but this elasticity may be augmented and the molding also strengthened by forming transverse 5 beads 8 thereon, as shown in Fig. 4. The tongued edges of the shingles may be held down by cleats 9, hooking over the tongues and nailed to the roof.

Another mode of securing the molding to 10 the roof is shown in Fig. 5. In this instance a rather wide cleat or shingle having its opposite edge bent up and doubly folded so as to form two grooves in each edge, one to embrace the tongue on the shingles and the 15 other to receive the lower edge of the molding, is shown. The outer walls of the outer grooves of the cleat may have stamped therein inclined projections or grooves to be engaged by teats or projections on the lower edge of 20 the molding.

Other forms of locking lugs or projections may be stamped in the tongues and walls of the grooves, and I do not wish to be understood as confining myself to the form shown.

25 It will be advantageous to stamp short beads in the body of the shingles extending at angles from the corners toward the lower edge, so as to direct rain-water from the joints at the adjacent courses of the shingles toward 30 the middle of the shingles.

As shown in Fig. 6, a cleat 11, that engages the groove at the upper edge of the shingle, and having a standing part 12 to brace the joint, may be used to obtain a firm and se- 35 cure joint.

What I claim, and desire to secure by Letters Patent, is—

1. A shingle having a tongue and a groove with oppositely projecting lugs, the lugs on 40 the tongue and groove being respectively in

different planes whereby the shingle may be superposed laterally upon a similar shingle and the lugs brought under one another without distending or straining the parts, substantially as and for the purpose described. 45

2. A shingle having a tongue and a groove provided with oppositely projecting lugs having inclined edges to engage lugs on a similar shingle, substantially as described.

3. In a roof, the combination of a shingle 50 having a tongue or groove with projecting lugs, and a molding having a tongue or groove with projecting lugs, the lugs on the shingle and molding being respectively in different planes whereby the shingle and molding may 55 be superposed laterally upon each other and the lugs brought one under the other without distending or straining the parts to lock the same, substantially as described.

4. A metallic shingle having its upper edge 60 bent and folded to form a shoulder 5 and groove 10 and its lower edge bent and folded to form the inclined water-shedding edge 7 and tongue 6, substantially as described.

5. In a roof, metallic shingles having their 65 upper edges bent and folded to form shoulders 5 and grooves 10 and their lower edges bent and folded to form inclined water-shedding edges 7 and tongues 6, the tongues 6 entering the grooves 10 to form the cross seam, 70 combined with a cleat 11 having a standing part 12 secured under the seam and forming a brace therefor, substantially as described.

In testimony whereof I affix my signature in presence of two witnesses.

WILLIAM R. KINNEAR.

Witnesses:

A. J. SMART,
GEO. M. FINGEL.
